Inventor:

J. Morrison Hunter

UNITED STATES PATENT OFFICE.

J. M. HUNTER, OF NEW YORK, N. Y.

IMPROVEMENT IN APPARATUS FOR TRYING OILS.

Specification forming part of Letters Patent No. 30,575, dated November 6, 1860.

To all whom it may concern:

Be it known that I, J. M. HUNTER, of the city, county, and State of New York, have invented certain new and useful Improvements in the Process of Rendering or Trying Out Oil, &c.; and I do hereby declare that the following is a full, clear, and exact description thereof, reference being had to the accompanying drawings, forming a part of this specification.

The chief objects of my invention are the application of boiler-heat to whale-blubber or other similar materials without burning such substances, and the subjection of said materials to the thorough action of a press within the boiler, both the boiling action and the pressing action being simultaneously applied. By applying heat and great pressure at the same time the oil is more rapidly expressed, and at the same time a larger per cent. of oil or fatty matter is obtained.

My invention consists in the combination of a boiler and press, the latter being placed within the former, for the purpose of rendering blubber or other fatty matters by the simultaneous application of boiler-heat and thorough action of a press.

The accompanying drawings represent a boiler and furnace, with a press contained within the boiler, Figure 1 being a central longitudinal section. Fig. 2 is a top view. Fig. 3 is a vertical transverse section at the red line X Y, Fig. 1.

In these drawings a sheet-iron furnace is represented with side walls, D, a fire-place, G, flue E, and smoke-pipe I. Within this furnace is placed a semi-cylindrical boiler, A, the bottom and sides of which are exposed to the heat of the flue E, as shown in Figs. 1 and 3, the direction of the smoke and heated air being indicated by red arrows. The boiler has large doors B, for introducing blubber or other material, and also several small openings, C, through which the contents of the boiler may be conveniently stirred by flexible scrapers or other means.

A crib for receiving the blubber or other material is arranged within the boiler, the bottom and sides of the same consisting of the T-shaped bars supported by suitable ribs. This crib prevents the scraps or other solid matter

from burning by coming in contact with the sides of the boiler, and at the same time it allows the oil to pass freely out of the crib between the T-shaped bars. The crib also serves as a press-hoop, in which the scraps are pressed by the movable heads or followers L, which are operated by the right-and-left-hand screw M, in connection with the gear-wheels N and R and hand-wheel S. There are four of these heads L, thus forming two presses, as it were, within the boiler. These heads L being set apart, as seen in Fig. 1, the blubber or other material is put into the crib J and the doors B are closed. Then heat is applied to the boiler by means of the furnace. The oil, as it is tried out, flows mostly from the crib J, filling the lower part of the boiler. This oil may be drawn off through faucet V from time to time, thus preventing the necessity of transmitting the heat through a large stratum of oil to the scraps within the crib, and also preventing the danger of a great accumulation of highly-heated oil within the boiler—a consideration of great importance when rendering oil on shipboard.

After the blubber or other matter is thoroughly heated the followers or heads L may be made to act upon the scraps with any desired force, thus expressing the oil at the same time that the heat of the boiler is continued.

The crib may be made of perforated flat or round bars, or of perforated plates, or with wire-gauze, or otherwise; and the various details of my apparatus may be somewhat varied without departing from my invention, so long as the construction and operation are substantially the same.

I am aware that in various modes of stirring the contents of the boiler while rendering blubber or other fatty substances more or less pressure has been employed; therefore I confine my claims to the use of a "press," properly so called, or to devices which will produce a thorough expression of the oil or fatty matter instead of a smaller portion of the same, as heretofore accomplished.

In the present application I confine my claims to the apparatus above described, leaving the process for a separate application for Letters Patent.

Having thus fully described my invention,

what I claim, and desire to secure by Letters Patent of the United States, is—

1. The above-described arrangement and combination of the press and boiler, the former being placed within the latter, for the purpose of rendering oils or other fatty matters by thoroughly pressing the scraps while the same are exposed to the boiler-heat or steam-heat, substantially in the manner and for the purposes described.

2. The use of the crib for preventing the

scraps from coming in contact with the boiler, substantially as described.

3. The employment of the pressure-heads and right-and-left-hand screws, by means of which the oil may be separated from the scraps, substantially in the manner described.

J. MORRISON HUNTER.
